UNITED STATES PATENT OFFICE.

CHARLES T. BLOOMER, OF NEWARK, NEW YORK.

EGG-BOX PARTITION.

1,006,716.

Specification of Letters Patent. Patented Oct. 24, 1911.

Application filed July 17, 1911. Serial No. 638,898.

To all whom it may concern:

Be it known that I, CHARLES T. BLOOMER, a citizen of the United States, residing at Newark, in the county of Wayne and State 5 of New York, have invented a new and useful Egg-Box Partition, of which the following is a specification.

This invention relates to folding partitions for egg boxes and the like and has for 10 its primary object to provide partitions which can be collapsed or folded compactly to occupy a space within the extremities of one of the partitions.

A further object is to provide partitions 15 which will permit of the smallest possible size of container or box being used.

With the above and other objects in view this invention is embodied in the novel construction, arrangement and combination of 20 parts as hereinafter described and as shown in the accompanying drawings, in which similar reference characters indicate similar parts, and in which,

Figure 1 is a perspective view of the various partitions as in open position. Fig. 2 is a plan view thereof in folded position. Fig. 3 is a detail in elevation of the longitudinal partition. Fig. 4 is a detail in elevation of the longitudinal strip. Fig. 5 is a detail in elevation of one of the lateral partitions. Fig. 6 is a fragmental view in perspective of a modification.

The partition as herein described and as shown in the drawings is particularly 35 adapted for use in boxes adapted to contain twelve eggs arranged in two rows of six eggs each.

Referring specifically to the drawings, 40 10 designates the longitudinal partition and 11, five lateral partitions which are mounted centrally on the partition 10 and which are adapted to fold against the said partition, the partition 10 being provided with a series of open slots 16 in the upper edge 45 thereof which slots 16 have one edge thereof notched and a projecting tooth on the other edge thereof, and the lateral partitions 11 are provided with an open slot 13 arranged centrally at the lower edge thereof 50 and an aperture 15 spaced above the inner end of the said slot, whereby when the said partitions are brought together the teeth 18 engage in the apertures 15 to retain the parts in position.

55 At the respective ends of the lateral partitions 11 are provided open slots 13' on the

lower edge thereof and apertures 15' are disposed above the said slots. The respective slots 13' and apertures 15' of the various partitions 11 are in horizontal alinement and a longitudinal strip 12 having a series of open slots 16' in the upper edge thereof, which slots 16' have one edge thereof notched as indicated at 17' and a projecting tooth 18' on the other edge, is adapted to pass through the slot 13' to engage the teeth 18' in the apertures 15' of the partitions 11 to lock the said strip on the ends of the partitions. The apertures 15' are arranged below the center of the partitions 11 and the strip 12 is of a width less than half of the partitions 11. The lateral partitions 11 are spaced equally along the longitudinal partition thus forming twelve cells of equal dimensions. The strip 12 has its extremities 75 within the extremities of the partition 10, or in close proximity to the outer partitions 11 whereby upon the partitions 11 being folded against the partition 10 the same will not project beyond the extremity of the 80 partition 10 as clearly shown in Fig. 2. This permits the partitions to be folded together to occupy a space within the extremities of the partition 10 for convenience in containing said partitions within the box when 85 folded, the ends of the partitions 11 being connected or joined by the strip 12 permit them to be folded or unfolded simultaneously and also tends to retain the partitions 11 in position as the eggs are inserted therein. It will be noted that the strip 12 passes through several of the cells between the partitions but as the same is of a width less than half the width of the partitions 11 the 90 eggs can be placed within the cells as the 95 bulged or larger diameter of the eggs extends over the top of the strip. Thus the strip 12 does not interfere with the eggs contained within the cells and should the eggs strike the upper edge thereof the same will 100 bend outwardly to follow the natural shape of the egg. The strip 12 therefore allows the ends of the lateral partitions 11 to be connected or joined without adding to the 105 size of the box or extending the said partitions.

In Fig. 6 is shown a modified strip 12' which is a width equal to that of the partitions 11 and partition 10 and when the partitions 11 are connected by the strip 12' 110 they are capable of being folded the same as when provided with the narrower strip

12. It is preferable however to use the narrower strip 12 which lies below the center of the partitions 11 for convenience in retaining the eggs therein without bulging the said strip outward as would be the case with the strip 12'.

It will thus be seen that the objects aimed at are obtained and that the partitions are capable of being folded without bending over any of the ends of same or of the strip 12 thus permitting all of the parts to remain straight.

What is claimed as new is:—

A device of the character described comprising a longitudinal partition, a plurality of equally spaced lateral partitions mounted centrally thereto and forming a plurality of equally sized cells, and each having an open slot in the lower edge thereof at one end and an aperture above the said slot, and a longitudinal strip having a series of open

slots having the opposite edges thereof notched and toothed, the teeth engaging in the said apertures of the lateral partitions, the said strip lying below the center of the lateral partition and passing through a number of the cells, and being of shorter length than the longitudinal partition with the extremities thereof lying within the extremities of the longitudinal partition, whereby the device may be used with the smallest possible container and whereby the said strip and lateral partitions may be folded against the longitudinal partition.

In testimony that I claim the foregoing as my own, I have hereto affixed my signature in the presence of two witnesses.

CHARLES T. BLOOMER.
